UNITED STATES PATENT OFFICE.

ALTON P. SLADE, OF ROCHESTER, NEW YORK, ASSIGNOR TO GLEASON WORKS, OF ROCHESTER, NEW YORK, A CORPORATION OF NEW YORK.

DRESSING WHEEL.

Application filed September 5, 1924. Serial No. 736,095.

My invention relates to a dressing wheel for truing the surfaces of a grinder such as used for grinding gears and like purposes.

The object of the invention is to afford a practicable and simple arrangement which can be readily operated, and maintains correct and accurate surfaces on a rotary face mill or other type of grinder.

Still another purpose of the improvement is to provide the periphery of a dressing wheel with a series of diamonds or analogous elements which serve as the operating or trimming medium on the dressing wheel.

Still an additional object of the invention is to afford a diamond dressing wheel, in which the diamonds or analogous elements are held securely in place and in such a way as to insure their outermost points or operating portions being a uniform distance from the rotary axis of the wheel.

With these ends in view, the invention comprises a construction that will appear clearly from the following description when read in conjunction with the accompanying drawings, the novel features being pointed out in the claims following the description.

In the drawings:

Fig. 1 is an enlarged side elevation of part of a dressing mechanism, illustrating a dressing wheel constructed in accordance with this invention.

Fig. 2 is a plan view of the dressing wheel and support.

Fig. 3 is an enlarged side view, partially in section, of the carrier forming part of the dressing wheel, and in which the diamonds are mounted.

Fig. 4 is an enlarged sectional view on line 4-4 of Fig. 3, and

Fig. 5 is an enlarged sectional view taken centrally of the dressing wheel.

The dressing wheel forming the subject matter of this invention is intended for use primarily in connection with a grinding wheel of the type illustrated in co-pending application Serial Number 724,356, filed July 5, 1924, and may be assembled in the manner disclosed in my co-pending application Serial Number 736,094 filed September 5, 1924, now Patent #1,601,378, dated September 28, 1926.

In the structure shown, 1 designates a portion of a rotary annular face mill type of grinder, having movement about an axis parallel to the surface 2, while 3 indicates

the operating faces to be dressed. The dressing wheel, which will presently be described in detail, is mounted on a support 4 that is reciprocated by any suitable mechanism, to carry the dressing wheel back and forth across an operative surface of the grinder.

The support 4 preferably moves straight across the surface to be dressed, while the dressing wheel has rotative movement upon an axis 5 which is arranged at other than a right angle to the direction of travel of the support 4. By adjusting the axis 5 of the dressing wheel to the proper acute angle relatively to the direction of movement of the support 4, the dressing wheel is caused to rotate by its engagement with the rotary grinder, the operating surfaces on the latter being brought to true and accurate form by movement of the dressing wheel. The operative portion of the dressing wheel consists of a series of diamonds arranged and held in place in the following manner.

A carrier is provided having a series of radially extending tubular retainers 6 each of which is preferably split at 7, or is otherwise provided with openings in its side wall. The diamond carrier is undercut on both sides of the tubular retainers 6 as shown at 8. 9 designates the diamonds located in the tubular retainers 6, while 10 are coil springs arranged against the inner faces of the diamonds and located in spring receiving openings of reduced diameter extending inwardly from the tubular retainers. 11 designates a binder such as type metal, or other similar material that can be flowed into and around the tubular retainers, and around the diamonds, to hold the latter in their predetermined position.

During assembling, the diamonds are held in place against a fixed positioning wall by the springs 10, as more thoroughly described in my co-pending application already mentioned, and the binder 11 serves to hold the diamonds in their proper position and relationship, so that the outermost or operative points of the diamonds are at equal distances from the rotary axis of the wheel. This arrangement insures a uniform and correct action of the diamonds on the surface to be dressed. It will be understood that after the binder 11 is in place, the springs 10 are imbedded therein in contact with the diamonds.

The carrier just described is suitably

mounted on a hub 12 which rotates in bearings in a frame 13, the latter being adjustably held in a cup 14. Adjustment of the frame 13 is had by turning the latter in cup 14 until the desired position of the dressing wheel is secured, whereupon the frame 13 is retained in place by tightening the nut 15 which engages pin 16 carried by the bottom of frame 13 and extending through the bottom of the cup 14.

While I have described the invention with reference to a particular embodiment, it is susceptible of various modifications and departures, and this application is intended to cover any changes coming within the underlying features of the improvement as set forth herein, or contemplated within the scope of the following claims.

I claim:

- 20 1. A dressing wheel comprising a carrier having a series of radially extending tubular retainers with openings in their side walls, spring receiving openings of reduced diameter extending inwardly from the tubular retainers, diamonds located in said tubular retainers, with their outermost points

spaced equally from the axis of the wheel, coil springs located in said reduced openings and engaging the inner surfaces of the diamonds, and a binder surrounding and filling the tubular retainers and spring openings and acting to hold the diamonds in position.

2. A dressing wheel comprising a carrier having a series of radially extending tubular retainers formed integral with the carrier, diamonds positioned in the retainers, coil springs located between the bottoms of the tubular retainers and the innermost surfaces of the diamonds, and a binder filling and surrounding the tubular retainers and acting to hold the diamonds therein.

3. A dressing wheel comprising a carrier having a series of radially extending tubular retainers formed integral with the carrier, diamonds positioned in the retainers, and a binder filling and surrounding the tubular retainers and acting to hold the diamonds therein.

In witness whereof, I have hereunto signed my name.

ALTON P. SLADE.
